[57] CLAIM

The ornamental design for an electrode holder for pH meters and the like, as shown and described.

DESCRIPTION

FIG. 1 is a perspective view of an electrode holder for pH meters and the like embodying my new design.
FIG. 2 is a side elevational view, with the opposite side being a mirror image.

FIG. 3 is a front elevational view taken along line 3—3 of FIG. 2.

FIG. 4 is a top plan view taken along line 4—4 of FIG. 2.

FIG. 5 is a rear elevational view taken along line 5—5 of FIG. 2.
